SHEET HANDLING APPARATUS

Samuel A. Huffman, Avalon, Pa., assignor to Miller Printing Machinery Co., Pittsburgh, Pa., a corporation of Pennsylvania

Application April 28, 1941, Serial No. 390,639

36 Claims. (CL 271—77)

This invention relates to sheet handling apparatus and more particularly to apparatus in which sheets are advanced on a carrier and in which means are provided for positioning the sheets on the carrier during such advance. The invention relates still more particularly to sheet handling apparatus of the type comprising endless sheet supporting means bodily advanceable with a sheet thereon without partaking of endwise movement and adapted to partake of endwise movement upon bodily retraction thereof to deliver the sheet and to sheet positioning means for use therewith and means for operating the sheet positioning means.

The invention will be described by way of explanation and illustration as embodied in sheet handling apparatus of the type employing an oscillatable carrier having thereon endless tapes upon which sheets are advanced individually, one sheet upon each cycle of operation of the carrier. As the carrier advances with a sheet thereon the tapes do not partake of endwise movement but are stationary relatively to the shafts or pulleys around which they extend. Upon retraction of the carrier the tapes partake of endwise movement to deliver the sheet. The effect is that the carrier advances beneath the sheet and with the sheet resting upon its upper surface and then is withdrawn from under the sheet but without exerting substantial friction on the sheet, whereupon the sheet is free to fall upon a pile or other support.

In sheet handling apparatus of the type mentioned which is desirably employed in delivering sheets from printing presses and other instrumentalities acting thereon sequentially means are provided for holding the sheets down on the tapes of the oscillatable carrier during advance of the carrier, as otherwise the sheets would not remain in place but would tend to have their forward edges blown up or to undesirably shift position on the carrier, particularly when the apparatus is operated at high speed. Various means have heretofore been employed to position the sheets on the carrier. Such means have not proved entirely satisfactory. The operation of the positioning means must be very accurately timed to the oscillation of the carrier in order to insure proper delivery of the sheets. The actual amplitude of movement of the carrier varies a fraction of an inch at different speeds due to gear lash and the relatively high stresses on the parts at high speeds. In the sheet positioning devices heretofore employed differences in amplitude of oscillation of the carrier have

resulted in operation of the positioning means at different times in the cycle of the carrier, resulting in non-uniform delivery of the sheets. Moreover, in such positioning devices the operation at high speeds has been such as to subject the parts to great shock and strain, shortening the life of the structure and hastening maladjustment and the necessity of repair.

I provide sheet handling apparatus employing sheet positioning means operable at the proper point in the cycle of the apparatus at all times and in which undue shock and strain upon the parts is obviated. I preferably operate the sheet positioning means by means having rolling contact and desirably I employ a free wheeling clutch idleable upon oscillation of the carrier in one direction and operable upon oscillation of the carrier in the opposite direction to move the positioning means between operative and inoperative positions. Preferably the positioning means are maintained in operative position during advance of the carrier, this desirably being effected by resilient means, and upon the beginning of the retractive movement of the carrier the free wheeling clutch is engaged to render the positioning means inoperative, this preferably being accomplished by the rolling contact means above mentioned. Upon advance of the carrier the rolling contact means and free wheeling clutch preferably simply idle and perform no operative function. The term "free wheeling clutch" is used herein to denote a connection, preferably, though not necessarily, rotary, which transmits motion from a driving member to a driven member when the driving member operates in one direction but does not transmit such motion when the driving member operates in the opposite direction.

I preferably employ positioning means in the nature of fingers carried by a turnable shaft so that the fingers are swung to and from operative position upon turning of the shaft through a small angle. The fingers cooperate with the carrier to position a sheet thereon during the forward or advancing movement of the carrier in each cycle of operation of the sheet handling apparatus. Desirably the positioning means comprise a portion acting as a stop or guide to determine the position lengthwise of the carrier of the forward edge of the sheet and a portion pressing down the sheet adjacent its forward edge upon a portion of the carrier. However, it is to be understood that the term "positioning means" as used herein is not so limited but relates to any means having a positioning function relatively to

the sheet and carrier. Such means may, for example, comprise only the stop or guide means or only the means for pressing the sheet down against the carrier, the other function in either case being performed by other means or conceivably in some instances being omitted.

In the description to follow the positioning means will be referred to as grippers, it being understood that while in the form shown separate stop and holding portions are employed either of such portions alone might be operated according to my invention and in such case would be considered as a gripper, although in some cases it might not actually have a gripping function. I shall refer to the shaft upon which the grippers are mounted as the gripper shaft. Preferably I provide a spring always urging the gripper shaft to turn the grippers to operative position. Upon the forward movement of the carrier the grippers are down in operative position to position the sheet on the carrier. They remain in this position until the instant when the carrier begins its rearward or retracting movement. At such instant the free wheeling clutch is engaged to turn the gripper shaft to raise the grippers. When the grippers are raised to a predetermined point a latch preferably engages to hold them in raised or inoperative position during at least a predetermined portion of the retracting movement of the carrier and while the sheet is passing beneath the raised grippers. Thereafter, and preferably as the carrier approaches the end of its retracting movement, the latch is rendered inoperative and the aforementioned spring turns the gripper shaft to return the grippers to operative position.

Other details, objects and advantages of the invention will become apparent as the following description of a present preferred embodiment thereof proceeds.

In the accompanying drawings I have shown a present preferred embodiment of the invention, in which

Figure 1 is a partial side elevational view of sheet delivery apparatus, parts having no relation to the present invention being omitted;

Figure 2 is a fragmentary plan view to enlarged scale of a portion of the structure shown in Figure 1;

Figure 3 is a fragmentary plan view to still further enlarged scale of a portion of the structure shown in Figure 2;

Figure 13 is a vertical longitudinal cross-sectional view taken on the line XIII—XIII of Figure 11; and

Figure 14 is a fragmentary vertical longitudinal cross-sectional view taken on the line XIV—XIV of Figure 3.

Referring now more particularly to the drawings, there is shown a sheet delivery apparatus comprising opposed side frame members 2 in which the sheet handling or delivery mechanism is mounted. The apparatus will hereinafter be referred to as a delivery. The delivery is adapted for use in connection with a printing press or the like to deliver and pile up sheets treated sequentially therein. The sheets come to the delivery one at a time upon tapes 3 preferably operating at constant speed substantially equal to the linear speed of the surface of the press cylinder. The sheets move from right to left, viewing Figure 1. As each sheet approaches the left-hand end of the tapes 3 it is delivered to a carrier designated by reference numeral 4 which is horizontally oscillatable or reciprocable.

There is provided driving mechanism including an oscillatable gear segment 5 the upper portion only of which is shown in Figure 1. During operation of the apparatus the gear segment 5 oscillates longitudinally of the delivery. It meshes with a pinion 6 fixed on a shaft 7 carried by the delivery frame. The shaft 7 also has fixed thereto a gear 8 which meshes with a pinion 9 fixed to a shaft 10 also carried by the delivery frame. Fixed to the shaft 10 adjacent each of the side frames 2 is a sprocket 11. Carried by each of the side frames 2 is a stud 12 carrying a sprocket 13. Each of the sprockets 13 is in longitudinal alignment with one of the sprockets 11. A sprocket chain 14 meshes with each of the sprockets 11 and the corresponding sprocket 13 in alignment therewith. Idlers 15 and 16 cooperate with the respective sprocket chains 14, the idler 16 being provided with a take-up device 17.

Each of the sprocket chains 14 is provided with one or more special links 18. Each of such special links has a bracket portion to which is bolted by bolts 19 a casting 20. The opposed castings 20 together with means extending transversely of the delivery therebetween and connecting the same together and the mechanism carried thereby constitute the carrier 4 which delivers the sheets sequentially from the tapes 3 to the delivery pile. The delivery pile is not shown in the drawings but is positioned underneath the carrier 4 to receive sheets therefrom as such sheets are delivered or discharged by the carrier, as will presently be explained.

As the segment 5 oscillates the sprocket chains 14 likewise partake of endwise oscillation and such oscillatory motion is transmitted to the carrier 4. The operation of the delivery is timed to that of the press so that the carrier 4 is near the right-hand end of its stroke, viewing Figure 1, although moving toward the left when a sheet is delivered to it upon the tapes 3.

Fastened to the inside of each side frame member 2 is a carrier supporting and guiding rail 21. Each of the castings 20 carries a pair of rollers 22 which ride upon one of the rails 21. The castings 20 are joined together by a

transverse tie bar 30 which extends therebetween. Supported by the tie bar 30 are generally horizontally extending roller supporting rods 31 which extend toward the press and which carry at their extremities tape supporting and guiding rollers 32. Mounted in the carrier and journaled for rotation in bearings 36 carried by portions of the castings 28 is a tape drive shaft 33 carrying rollers 34 each in alignment with one of the rollers 32. An endless tape 35 extends around each of the pairs of aligned rollers 32 and 34. The shaft 33 also carries rollers 37 disposed intermediate the rollers 34 and the radius of each of which is substantially equal to the radius of each of the rollers 34 plus the thickness of each of the tapes 35, as shown in Figure 2. The purpose of the rollers 37 will presently be explained.

At one end the shaft 33 extends outwardly past the bearing 36, as shown in Figure 11, where it is provided with a reduced extension 38 (see also Figure 13). Fixed to the reduced extension 38 of the shaft 33 is the spider member 39 of a free wheeling clutch 40. Rotatably mounted about the extension 38 upon ball bearings 41 is a sleeve 42 to which is unitarily connected a pinion 43. Within the sleeve 42 and intermediate the arms of the spider 39 are cylindrical rollers 44. Each of the arms of the spider 39 has one generally radial face and another inclined face, as shown in Figure 13. When the pinion 43 is turned in the clockwise direction, viewing Figure 13, the rollers 44 will lie against the generally radial faces of the arms of the spider 39 and the spider will remain stationary, the pinion 43 and sleeve 42 turning therewith. When, however, the pinion 43 is turned in the counter-clockwise direction viewing Figure 13 the rollers 44 will be frictionally urged toward the inclined faces of the arms of the spider 39 and will tend to bind between the spider and the sleeve 42, thus causing the spider and with it the shaft 33 to turn with the pinion 43.

The pinion 43 meshes with a rack 45 formed on the under surface of one of the rails 21. Since the rack 45 is stationary and the carrier 4 of which the shaft 33 forms a part oscillates back and forth relatively thereto the pinion 43 will turn alternately in one direction and the other during oscillation of the carrier. When the carrier is moving out away from the press the pinion 43 turns in the clockwise direction, viewing Figure 13, and does not turn the shaft 33. When, however, the carrier is moving back toward the press the pinion 43 turns in the counter-clockwise direction, viewing Figure 13, and causes the shaft 33 to turn therewith. Consequently the shaft 33 turns only when the carrier is moving toward the press and not when it is moving away from the press. But turning of the shaft 33 in the counter-clockwise direction, viewing Figures 4 and 13, moves the tapes 35 endwise relatively to the rollers 32 and 34 and in the counter-clockwise direction about the axis of the shaft 33, viewing Figure 4. The outer surfaces of the tapes 35 lie approximately in the pitch line of the rack 45. The result is that when the carrier is moving away from the press the tapes 35 do not partake of endwise movement relatively to the rollers 32 and 34. When, however, the carrier moves back toward the press the tapes 35 partake of endwise movement relatively to the rollers 32 and 34, the linear speed of such movement of the tapes being substantially equal to the linear speed of movement

of the carrier so that the upper reaches of the tapes 35 between the rollers 32 and 34 will remain substantially stationary relatively to the side frames 2. A sheet resting upon the tapes 35 will thus be advanced in fixed position on the carrier when the carrier moves away from the press and when the carrier moves back toward the press it will to all intents and purposes move out from under the sheet, leaving the sheet free to drop onto the pile. The pinion 43 has a lateral projection 46 carrying a bearing portion 47 which bears against a bearing portion 48 on the rail 21 which carries the rack 45. At the opposite end of the shaft 33 is a roller 49 which is turnable relatively to the shaft 33 and which bears against the under surface of the opposite rail 21, as shown in Figure 6.

Mounted in the carrier 4 and extending between the castings 28 is a gripper shaft 28. The gripper shaft is turnable in bearings 24 in the castings 20 and has fixed thereto at intervals transversely of the apparatus grippers 25. Each gripper 25 comprises a finger 26 having a sheet positioning guide or stop portion 27 at its outer extremity adapted when the gripper is down in operative position to engage the forward edge of a sheet fed to the carrier to thereby position the sheet on the carrier. Each gripper also comprises a resilient holdown member 28 whose extremity 29 is adapted to bear upon one of the above mentioned rollers 37 carried by the shaft 33. Each of the holdown members 28 is fastened to its finger 26 at 30 and its tension may be adjusted by a tension adjusting screw 51. The gripper structure per se forms no part of the present invention and is claimed in copending application Serial No. 393,555. The grippers are shown in operative position in Figure 5. When in such position the extremity 29 of each holdown member 28 bears upon one of the rollers 37, the stop portion 27 being offset laterally from the roller and extending downwardly below the surface of the roller generally toward the axis of the shaft 33, as shown in Figure 5. The grippers are in the position shown in Figure 5 when a sheet is delivered to the carrier from the tapes 3. At such time the carrier is moving from right to left, viewing Figure 1. The sheet delivered by the tapes 3 moves somewhat faster than the carrier at the time it is received by the carrier and the forward edge of the sheet engages the stop portions 27 of the grippers whereby the sheet is positioned on the carrier, passing between the extremities 29 of the holdown members 28 and the surfaces of the rollers 37 to be gripped therebetween. The tension of the holdown members 28 is adjusted for the particular weight of stock being operated upon to insure that the forward edge of the sheet will enter between the holdown members 28 and the cooperating rollers 37 and be maintained thereby in position relatively to the carrier. The carrier advances toward the left, viewing Figure 1, with a sheet thus positioned and held in place thereon.

Carried by one of the side frames 2 is a track 52. The track 52 is fastened to the frame 2 by screws 53. Resilient material such as rubber 54 (Figure 8) is interposed between the track and the frame. This allows the track to be depressed somewhat toward the frame during operation of the apparatus, as will presently be described. The track is of generally wedge shape in cross section, as shown in Figure 7. It is very short as compared with the travel of the carrier and is posi-

tioned adjacent the left-hand end of the delivery viewing Figures 1 and 2.

Carried by one of the castings 20 and extending outwardly toward the adjacent frame member 2 which carries the track 52 is a stud 55. Fixed to the stud by a set screw 56 is a collar 57. Carried loosely upon the stud 55 is a sleeve 58 having a radial flange 59. Fixed to the gripper shaft 23 is an arm 60. Pivoted to the flange 59 at 61 and to the arm 60 at 62 is a link 63. Surrounding the stud 55 and having one end connected with the collar 57 at 64 and the other end connected with the flange 59 at 65 is a coil spring 66. The coil spring is applied so that, the stud 55 being considered stationary, it urges the sleeve 58 and the flange 59 to turn thereabout in the counter-clockwise direction, viewing Figure 8, whereby to turn the gripper shaft 23 in the counter-clockwise direction to move the grippers toward operative position as they are shown in Figure 5.

Rotatably carried by the outer end of the stud 55 is an externally threaded sleeve 67 having integral therewith one portion 68 of a roller adapted to cooperate with the track 52. Threaded onto the sleeve 67 is an internally threaded sleeve 69 carrying a complementary portion 70 of the roller. The sleeve 69 may be adjusted relatively to the portion 68 to enable the roller to cooperate properly with the track 52 whereupon the sleeve 69 is fastened to the sleeve 67 by a set screw 71. The sleeve 67 has a reduced extension 72 to which is fixed by a set screw 73 a sleeve 74. A coil spring 75 surrounds the sleeve 58 and is connected with the sleeve 74 at 76, as shown in Figure 7. A sleeve 77 surrounds the coil spring 75 to keep out dust and dirt. The sleeve 77 lies loosely between the flange 59 and the sleeve 74.

The coil spring 75 cooperating with the sleeve 58 forms a free wheeling clutch between the roller 68-70 and the sleeve 58 which carries the flange 59. The spring is connected only to the flange 74, its opposite end being free. Thus when the roller 68-70 is turned in the counter-clockwise direction about the axis of the stud 55 viewing Figure 8 the spring 75 has no function and the roller, sleeve 67, collar 74 and spring 75 turn alone. When, however, the roller is turned in the opposite direction the spring 75 which engages the sleeve 58 frictionally grips such sleeve and the sleeve and its flange 59 are turned in the clockwise direction viewing Figure 8, thus turning the gripper shaft 23 in the clockwise direction and raising the grippers to inoperative position.

The gripper shaft 23 has a reduced extension 78 extending toward the adjacent side frame 2 from one of the castings 20. Fixed to the extension 78 is an arm 79 (Figure 14). The arm 79 has a cam portion 80 and a locking portion 81. Pivoted to the adjacent casting 20 at 82 is a latch 83 having an operative or engaging portion 83a. The latch 83 is urged to turn in the clockwise direction, viewing Figure 2, by a coil spring 84 connected with the latch at 85 and with the casting at 86. The spring 84 maintains the latch 83 in contact with the arm 79. As the shaft 23 with its extension 78 turns in the counter-clockwise direction, viewing Figure 14, the latch 83 rides upon the cam portion 80 of the arm 79 and ultimately drops off of such cam portion into the locking portion 81, thus holding the shaft 23 against movement in the clockwise direction, viewing Figure 14.

A detent 87 in the path of movement of the

latch 83 during oscillation of the carrier 4 is pivoted at 88 to a bracket 89 connected to the frame by bolts 90. The detent 87 normally depends in the position shown in Figure 12. When in such position it has a generally vertical latch engaging face 91 and a generally horizontal face 92 which in the position shown in Figure 12 lies against a generally horizontally extending stop 93. Thus as viewed in Figure 12 the detent 87 is free to turn in the clockwise direction about the axis of the pivot 88 but cannot turn in the counter-clockwise direction.

The operation of the apparatus is as follows. When the carrier 4 is at the right-hand end of its stroke, viewing Figure 1, and ready to move toward the left a sheet is being moved toward the left on the tapes 3. At such time the grippers are in operative position, as shown in Figure 5. As the carrier moves toward the left the sheet catches up with it when the carrier has move approximately one-third of its stroke and is positioned and gripped by the grippers as above explained. The carrier with the sheet thereon then continues its movement toward the left, viewing Figure 1. The pinion 43 is in mesh with the rack 45 but the spider 39 and consequently the shaft 33 does not turn. As the carrier nears the end of its stroke the roller or wheel 68-70 rides upon the track 52 but does not affect the sleeve 58 or the mechanism connected therewith. Thus when the carrier is moving toward the left, viewing Figure 1, the free wheeling clutch which incorporates the spring 75 idles. The spring 66 holds the grippers down in operative position.

The parts remain in such position until the instant the carrier begins its return stroke toward the right, viewing Figure 1. At such instant the pinion 43 and sleeve 42 cause the spider 39 and the shaft 33 to turn in the clockwise direction, viewing Figure 5. Also the roller or wheel 68-70 rides on the track 52, turning in the clockwise direction, viewing Figure 8. When the roller turns in the clockwise direction the spring 75 grips the sleeve 58 and turns such sleeve and the flange 59 in the clockwise direction, viewing Figure 8, to turn the gripper shaft in the clockwise direction against the action of the spring 66 whereby to raise the grippers to inoperative position. The grippers continue to be raised until the pivotal connection 61 reaches dead center between the axis of the stud 55 and the pivotal connection 62. At such time the grippers are in their extreme raised position. However, at approximately the same time the latch 83 drops into the locking portion 81 of the arm 79. Thus any further turning of the sleeve 58 and flange 59 in the clockwise direction, viewing Figure 8, is prevented. From that point on the roller or wheel 68-70 will slide frictionally along the track 52. This will cause the right-hand end of the track, viewing Figure 8, to be somewhat depressed since the rolling engagement will have changed to sliding engagement. For this reason the track 52 is resiliently mounted. The roller slides along the track for only a short distance until it passes off of the end of the track. The carrier moves back toward the press while the tapes 35 roll out from under the sheet which passes beneath the raised grippers and falls upon the pile. As movement of the carrier toward the press continues the latch 83 strikes the surface 91 of the detent 87, which turns the latch in the counter-clockwise direction about the axis of the pivot 88, viewing Figure 3, and releases the gripper shaft 33

which is then turned to move the grippers down into operative position by the spring 66. As the carrier begins its movement toward the left, viewing Figure 1, in the succeeding cycle the latch 82 strikes the surface of the detent 81 generally opposed to the surface 91 and swings the detent out of the way in the clockwise direction about the axis of the pivot 88, the detent thereafter swinging back by gravity to the position shown in Figure 12.

While I have shown and described a present preferred embodiment of the invention it is to be distinctly understood that the invention is not limited thereto but may be otherwise variously embodied within the scope of the following claims.

I claim:

1. Sheet handling apparatus comprising a movable carrier against which a sheet is adapted to be positioned, means for positioning the sheet relatively to the carrier movable to and from operative position relatively to the carrier and means including a rotary member and a member along which said rotary member is adapted to roll upon movement of the carrier to move the positioning means relatively to the carrier.

2. Sheet handling apparatus comprising a movable carrier against which a sheet is adapted to be positioned, means for positioning the sheet relatively to the carrier movable to and from operative position relatively to the carrier and means including a free wheeling clutch for moving the positioning means relatively to the carrier.

3. Sheet handling apparatus comprising an oscillatable carrier against which a sheet is adapted to be positioned, means for positioning the sheet relatively to the carrier movable to and from operative position relatively to the carrier and means including a member freely turnable when the carrier moves in one direction and turnable when the carrier moves in the opposite direction to move the positioning means relatively to the carrier.

4. Sheet handling apparatus comprising an oscillatable carrier against which a sheet is adapted to be positioned, means for positioning the sheet relatively to the carrier movable to and from operative position relatively to the carrier and normally urged toward operative position and means movable in one direction upon movement of the carrier in one direction to move the positioning means toward inoperative position and idleable in the direction opposite the direction of its first mentioned movement upon movement of the carrier in the direction opposite the direction of its first mentioned movement.

5. Sheet handling apparatus comprising an oscillatable carrier against which a sheet is adapted to be positioned, means for positioning the sheet relatively to the carrier movable to and from operative position relatively to the carrier, means operable upon movement of the carrier in one direction to move the positioning means to inoperative position and idleable upon movement of the carrier in the opposite direction and means for holding the positioning means in inoperative position.

6. Sheet handling apparatus comprising an oscillatable carrier against which a sheet is adapted to be positioned, means for positioning the sheet relatively to the carrier movable to and from operative position relatively to the carrier, means operable upon movement of the carrier in one direction to move the positioning

means to inoperative position and idleable upon movement of the carrier in the opposite direction and latch means operable upon movement of the positioning means to inoperative position to maintain the same in such position.

7. Sheet handling apparatus comprising an oscillatable carrier against which a sheet is adapted to be positioned, means for positioning the sheet relatively to the carrier movable to and from operative position relatively to the carrier, means operable at a predetermined point in the movement of the carrier to move the positioning means to one of operative and inoperative positions, latch means operable upon movement of the positioning means to said position to maintain the same therein and a detent engageable with the latch means at another predetermined point in the movement of the carrier to render the latch means inoperative.

8. Sheet handling apparatus comprising an oscillatable carrier against which a sheet is adapted to be positioned, means for positioning the sheet relatively to the carrier movable to and from operative position relatively to the carrier, means operable at a predetermined point in the movement of the carrier to move the positioning means to one of operative and inoperative positions, latch means operable upon movement of the positioning means to said position to maintain the same therein and a detent engageable with the latch means at another predetermined point in the movement of the carrier to render the latch means inoperative, said detent being mounted in the path of the latch means during oscillation of the carrier and so as to be moved aside by the latch means upon movement of the carrier in one direction of oscillation.

9. Sheet handling apparatus comprising a carrier against which a sheet is adapted to be positioned, means for positioning the sheet relatively to the carrier movable to and from operative position relatively to the carrier, cam means connected with the positioning means, a latch bearing against the cam means when the positioning means is in one position and a stop cooperating with the latch when the positioning means is in another position to maintain the positioning means in such position.

10. Sheet handling apparatus comprising a carrier against which a sheet is adapted to be positioned, means for positioning the sheet relatively to the carrier movable to and from operative position relatively to the carrier, the positioning means being urged toward one of operative and inoperative positions, means for moving the positioning means to the other of said positions, a latch adapted when the positioning means is in the last mentioned position to maintain the same in said position, the latch being urged into position to maintain the positioning means in said last mentioned position, and means rendering the latch inoperative when the positioning means is in the first mentioned position.

11. Sheet handling apparatus comprising a carrier against which a sheet is adapted to be positioned, means for positioning the sheet relatively to the carrier movable to and from operative position relatively to the carrier, resilient means urging the positioning means toward one of operative and inoperative positions, means for moving the positioning means to the other of said positions, means for holding the posi-

tioning means in the last mentioned position and means predeterminedly operable to render the holding means inoperative to permit the positioning means to move to the first mentioned position.

12. Sheet handling apparatus comprising a carrier against which a sheet is adapted to be positioned, a shaft, means for positioning the sheet relatively to the carrier carried by the shaft, means for turning the shaft to move the positioning means between operative and inoperative positions relatively to the carrier, a projection on the shaft and means cooperable with said projection to maintain the shaft in predetermined position.

13. Sheet handling apparatus comprising a movable carrier against which a sheet is adapted to be positioned, means for positioning the sheet relatively to the carrier movable to and from operative position relatively to the carrier and means including a wheel and a track along which said wheel rolls upon movement of the carrier to move the positioning means relatively to the carrier.

14. Sheet handling apparatus comprising a movable carrier against which a sheet is adapted to be positioned, means for positioning the sheet relatively to the carrier movable to and from operative position relatively to the carrier and means including a wheel and a track along which said wheel rolls upon movement of the carrier to move the positioning means relatively to the carrier, one of the wheel and track having a generally wedge shaped tread portion and the other thereof having a recessed tread portion to receive said first mentioned tread portion.

15. Sheet handling apparatus comprising a movable carrier against which a sheet is adapted to be positioned, means for positioning the sheet relatively to the carrier movable to and from operative position relatively to the carrier and means including a wheel and a resiliently mounted track along which said wheel rolls upon movement of the carrier to move the positioning means relatively to the carrier.

16. Sheet handling apparatus comprising a movable carrier against which a sheet is adapted to be positioned, means for positioning the sheet relatively to the carrier movable to and from operative position relatively to the carrier, a turnable member, means connected with said turnable member eccentrically thereof, connections with said last mentioned means effective upon turning of said turnable member for moving the positioning means between operative and inoperative positions and means limiting turning of said turnable member to prevent said means connected therewith from substantially passing dead center relatively to said connections.

17. Sheet handling apparatus comprising a movable carrier against which a sheet is adapted to be positioned, means for positioning the sheet relatively to the carrier movable to and from operative position relatively to the carrier, means including a wheel and a track along which said wheel rolls upon movement of the carrier to move the positioning means relatively to the carrier and means limiting the turning movement of the wheel upon predetermined movement of the positioning means relatively to the carrier.

18. Sheet handling apparatus comprising a movable carrier against which a sheet is adapted to be positioned, means for positioning the

sheet relatively to the carrier movable to and from operative position relatively to the carrier, means including a wheel and a track along which said wheel rolls upon movement of the carrier to move the positioning means relatively to the carrier and means limiting the turning movement of the wheel upon predetermined movement of the positioning means relatively to the carrier so that the carrier slides along the track during a portion of its travel therealong, the track being mounted to yield away from the wheel during said sliding of the wheel therealong.

19. Sheet handling apparatus comprising an oscillatable carrier against which a sheet is adapted to be positioned, means for positioning the sheet relatively to the carrier movable to and from operative position relatively to the carrier, and means including a wheel and a track along which said wheel rolls and a free wheeling clutch to move the positioning means relatively to the carrier upon movement of the carrier in one direction, said clutch being idleable upon movement of the carrier in the opposite direction.

20. Sheet handling apparatus comprising a shaft, a sheet support, sheet positioning means for positioning sheets on the support, connections between the shaft and positioning means to move the latter toward and from operative position upon turning of the shaft, means urging the shaft to turn in one direction and means including a free wheeling clutch for turning the shaft in the opposite direction.

21. Sheet handling apparatus comprising an oscillatable carrier, a shaft, sheet positioning means cooperable with the carrier, connections between the shaft and positioning means to move the latter toward and from operative position upon turning of the shaft and means including a free wheeling clutch operable upon movement of the carrier in one direction for turning the shaft.

22. Sheet handling apparatus comprising an oscillatable carrier, a shaft, sheet positioning means cooperable with the carrier, connections between the shaft and positioning means to move the latter toward and from operative position upon turning of the shaft, a stationary operating member and a movable operating member adapted upon movement of the carrier to be moved by contact with the stationary operating member, the movable operating member being connected with the shaft through a free wheeling clutch to turn the shaft upon movement of the carrier in one direction only.

23. Sheet handling apparatus comprising an oscillatable carrier, sheet positioning means cooperable with the carrier, a stationary operating member and a movable operating member adapted upon movement of the carrier to be moved by contact with the stationary operating member and connected with the positioning means through a free wheeling clutch, the movable operating member riding freely over the stationary operating member upon advance of the carrier with a sheet carried thereby without affecting the positioning means and operating through the free wheeling clutch to render inoperative the positioning means upon retraction of the carrier.

24. Sheet handling apparatus comprising endless sheet supporting means bodily advanceable with a sheet thereon without partaking of endwise movement and adapted to partake of end-

wise movement upon bodily retraction thereof to deliver the sheet, sheet positioning means co-operable with the sheet supporting means and means including a free wheeling clutch idleable upon advance of the sheet supporting means and operable upon retraction of the sheet supporting means to render the positioning means inoperative.

25. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means to position a sheet thereon during advance of the sheet supporting means and means including a turnable shaft and a roller connected with the shaft and coaxial therewith and rolling upon a track during movement of the sheet supporting means for turning the shaft to render the positioning means inoperative upon retraction of the sheet supporting means.

26. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means to position a sheet thereon during advance of the sheet supporting means and means including latch means for maintaining the positioning means inoperative upon retraction of the sheet supporting means.

27. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means and means for moving the positioning means between operative and inoperative positions comprising a roller turnable through less than one revolution upon each movement of the sheet supporting means in each direction.

28. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means, resilient means urging the positioning means to one of operative and inoperative positions, means for moving the positioning means to the other of said positions during bodily movement of the sheet supporting means and latch means for maintaining the positioning means in said last mentioned position.

29. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means, resilient means urging the positioning means to one of operative and inoperative positions and means including a free wheeling clutch idleable upon bodily movement of the sheet supporting means in one direction and operable upon bodily movement of the sheet supporting means in the oppo-

site direction for moving the positioning means to the other of said positions.

30. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means, resilient means urging the positioning means to operative position and means including a free wheeling clutch idleable upon advance of the sheet supporting means to permit the resilient means to render the positioning means operative and operable upon retraction of the sheet supporting means to move the positioning means to inoperative position.

31. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means, resilient means urging the positioning means to operative position, means including a free wheeling clutch idleable upon advance of the sheet supporting means to permit the resilient means to render the positioning means operative and operable upon retraction of the sheet supporting means to move the positioning means to inoperative position and latch means to maintain the positioning means in inoperative position.

32. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means, resilient means urging the positioning means to operative position, means including a free wheeling clutch idleable upon advance of the sheet supporting means to permit the resilient means to render the positioning means operative and operable upon retraction of the sheet supporting means to move the positioning means to inoperative position, latch means to maintain the positioning means in inoperative position during a predetermined portion of the retractive movement of the sheet supporting means and means for rendering the latch means inoperative to permit the resilient means to return the positioning means to operative position at the end of said predetermined portion of the retractive movement of the sheet supporting means.

33. Sheet handling apparatus comprising endless sheet supporting means bodily advanceable with a sheet thereon without partaking of endwise movement and adapted to partake of endwise movement upon bodily retraction thereof to deliver the sheet, sheet positioning means co-operable with the sheet supporting means, means inoperative upon advance of the sheet supporting means but operative upon retraction of the sheet supporting means to move the positioning means to inoperative position, latch means to maintain the positioning means in inoperative position during a predetermined portion of the retractive movement of the sheet supporting means and means for rendering the latch means inoperative at the end of said predetermined portion of the retractive movement of the sheet supporting means.

34. Sheet handling apparatus comprising a

movable carrier against which a sheet is adapted to be positioned, means for positioning the sheet relatively to the carrier movable to and from operative position relatively to the carrier and means including a wheel and a track with which the wheel interengages upon movement of the carrier to move the positioning means relatively to the carrier, one of the wheel and track having opposed portions relatively adjustable to alter the interengagement between the wheel and track.

35. Sheet handling apparatus comprising an oscillatable carrier against which a sheet is adapted to be positioned, means for positioning the sheet relatively to the carrier movable to and from operative position relatively to the carrier, means including a connection operable upon movement of the carrier in one direction only for moving the positioning means relatively to the carrier in one direction of movement of the positioning means and spring means for moving

the positioning means relatively to the carrier in the opposite direction of movement of the positioning means.

36. Sheet handling apparatus comprising an oscillatable carrier against which a sheet is adapted to be positioned, means for positioning the sheet relatively to the carrier movable to and from operative position relatively to the carrier, means operable at a predetermined point in the movement of the carrier to move the positioning means to one of operative and inoperative positions, latch means operable upon movement of the positioning means to said position to maintain the same therein, means operable at another predetermined point in the movement of the carrier to render said latch means inoperative and spring means operable upon rendering inoperative of the latch means to move the positioning means to the other of operative and inoperative positions.

SAMUEL A. HUFFMAN.
